UNITED STATES PATENT OFFICE.

FRANK F. BEALL, OF DETROIT, MICHIGAN, ASSIGNOR TO PACKARD MOTOR CAR COMPANY, OF DETROIT, MICHIGAN, A CORPORATION OF MICHIGAN.

MECHANISM FOR FORMING GEARS.

1,332,968.

Specification of Letters Patent.

Patented Mar. 9, 1920.

Original application filed December 23, 1914, Serial No. 878,733. Divided and this application filed April 29, 1918. Serial No. 231,423.

To all whom it may concern:

Be it known that I, FRANK F. BEALL, a citizen of the United States, and resident of Detroit, Wayne county, State of Michigan, 5 have invented certain new and useful Improvements in Mechanism for Forming Gears, of which the following is a specification.

This application is a division of application Serial No. 878,733 filed December 23, 10 1914, patented May 27, 1919, No. 1,305,050.

This invention relates to mechanism for forming gears.

One object of this invention is to provide 15 a machine for forging or pressing gears into shape as distinguished from cutting or casting them.

Other objects will appear from an examination of the following description taken in 20 connection with the accompanying drawings which form a part of the specification and in which:

Figure 1 is an elevation of a drop forge hammer of the type used for roughing out 25 the gear blank;

Fig. 2 is an elevation of a press adapted for carrying out one of the pressing operations of the invention;

Fig. 3 is a press similar to that shown in 30 Fig. 2 and is adapted for carrying out another of the pressing operations of the invention;

Fig. 4 is a fragmentary section through 35 the roughing die showing it in operating relation with the gear blank;

Fig. 5 is an end view of the die and blank shown in Fig. 4;

Fig. 6 is a view similar to Fig. 4 showing the finishing die;

Fig. 7 is an end view of the die and blank shown in Fig. 6;

Fig. 8 is an enlarged vertical section through one of the die presses showing the blank in position;

Fig. 9 is a plan view or horizontal section on the line 9—9 of Fig. 8;

Fig. 10 is an enlarged side view of a part of one of the die presses showing the locating lever in position;

Fig. 11 is an enlarged perspective view of the locating lever; and

Fig. 12 is a transverse section through the head of the locating lever.

In the form of the invention particularly set forth herein, a gear blank having a plain 55 face is drop forged, is then placed in a die press where a roughing die forms teeth of abnormal thickness and preferably of less height than the required finished tooth, is then subjected to a second die pressing operation in which a finishing die compresses the thick teeth to the desired contour and forces excess metal outwardly beyond the normal tops and perhaps at the ends of the teeth, and is then machined or ground to 60 remove the excess metal. The last step is the hardening of the finished gear. Gears made by this method will be found in most cases to be accurate enough for the finest work, but if desired a finishing cut may be 65 made on the faces of the teeth before hardening to give a still greater degree of accuracy.

A gear made in accordance with the above referred to method comprises teeth the faces 75 of which are compressed and die finished leaving the metal denser at and adjacent said faces, and the tops and ends of which have a cut finish where the excess metal has been removed either by machining or grinding.

The drawings illustrate suitable machinery for making gears like that above described. With some metals and with some sizes of gears the various forging and pressing steps may be carried out with one heating of the blank. For this purpose a suitable drop hammer 40 and two presses or similar machines 41 and 42 should be grouped together so that the gear blank may 85 first be forged at its greatest heat by the drop hammer 40, then transferred immediately to the press 41 where it receives the roughing operation, and then placed in the press 42 to be pressed under the finishing 90 die. Under certain circumstances, however, it may be desirable to reheat the blank between either the first and second or the second and third operations, or both. Also it will be understood that a single press may 95 be used instead of two presses by changing dies between operations, but this might necessitate reheating of the blank in all cases. Also, a single die pressing operation is sufficient for some gears, the finishing die being 100 used following the forging operation.

The drop hammer 40 may be a steam hammer as shown and the dies 43 and 44 are shaped to produce the blank B. The die block 43 is the stationary die and the die 44 is reciprocated toward and from the die 43 by the piston rod 45 and its piston operating in the steam cylinder 46. The presses 41 and 42 shown in Figs. 2 and 3 are identical except in the forms of their upper dies. In each, 47 represents the lower or stationary die resting on the table 48 and 49 is the press ram or support for the upper or movable die. The ram is operated by hydraulic pressure through a piston in the cylinder 50.

The press 41 has the roughing die 51 secured to its ram, and as the die moves downwardly its space forming parts 52 press into the blank B as shown in Figs. 4 and 5, forming thick and comparatively low teeth as shown in Fig. 5. The press 42 has the finishing die 53 secured to its ram, and as this die descends upon the blank that has been transferred from the press 41 the abnormally thick teeth are compressed between the space forming parts 54 of this die as shown in Figs. 6 and 7, thus condensing the metal along the tooth faces. In this operation there is a slight excess of metal which is allowed to flow beyond the normal tops of the teeth and outwardly to a limited extent at the ends of the teeth.

More particularly referring to the presses, attention is called to the further showing in Figs. 8 to 12 inclusive. The gear blank B is shown in position in the depression 59 in the die block 47. The latter is formed with a central bore 60 to receive a centering stud or pilot 61 extending from the center of the ram 49 and die 53. The die block 47 also has a series of projections 62 at the edge of the depression 59 for supporting the ends of the teeth of the gear during the pressing operation, it being understood that the inner faces of these projections are positioned slightly removed from the blank so that the metal of the teeth may be pressed outwardly a little beyond normal and later removed. The spaces 63 between the projections 62 provide clearance for the outer ends of the space forming parts 54 of the die 53 as the die descends vertically to form the gear.

In addition to the pilot 61 extending from the upper die 53, the latter is provided with a presser plate 64 which has a series of bolts 65 forming a sliding connection between the die and the plate. Springs 66 surround the bolts 65 and tend to press the plate downwardly away from the die, this movement being limited by the heads of the bolts striking the shoulders 67 in the bores 68 in which the bolts operate. This presser plate 64 follows the pilot 61 in contacting with the blank during the descent of the

ram and the springs hold the blank yieldingly in the depression 59 in position to be acted upon by the die 53. The plate, like the die 47, is formed at its edge with a series of projections 69 for supporting the inner ends of the teeth of the gear during the pressing operation, and the spaces 70 between the projections 69 provide for die clearance the same as spaces 63.

Means are provided for accurately locating or positioning the blank circumferentially before the upper die is brought down on the blank, as when the blank receives a roughing operation in one press or by one die and a second or finishing operation in a second press or by another die. After one die has started the formation of tooth spaces in the blank it is necessary that the blank should be properly located under the second die so that the space forming parts of the second die will accurately enter the spaces already roughly formed in the blank. In the present invention this circumferential positioning is done by a locating lever 71 which may be pivoted as shown to the stationary die block 47 at 72. The head 73 of this lever has a groove in one of its operating faces and a tooth on the opposite face and in the form shown the groove 74 is in its upper face and is adapted to receive one of the teeth or space forming parts 54 of the die 53, and the tooth 75 is in its lower face and is adapted to engage in one of the spaces between the teeth of the roughed out blank.

The lever 71 is shown in full lines in Fig. 8 in inoperative position and in dotted lines in operative position for locating the blank in proper circumferential relation to the die 53. Fig. 9 shows the lever inoperative and Fig. 10 shows how it lines up the teeth and spaces of the die and blank respectively. In operation, the blank is roughly positioned by hand with the tooth 75 of the locating lever in one of the tooth spaces of the blank. The ram is then brought down slowly until one of the die teeth enters the groove 74 and thereby definitely and accurately locates the blank under the pressure plate. Then the ram is raised sufficiently to permit the lever 71 to be removed and then brought down for the pressing operation.

The lever 71 may be manually operated by a pivotally connected hand lever 76 mounted on the die block 47 as by a link 77 and bracket 78. A spring 79 retracts the hand lever 76 and keeps the lever 71 normally in the inoperative position shown in full lines in Fig. 8.

It will be understood that the invention is not limited to the specific machine herein shown and described, but is capable of modification in various ways without departing from the scope of the claims.

Having thus described my invention, what I claim and desire to secure by Letters Patent is:—

1. In a machine of the class described, in combination, a blank support, a die having teeth to form tooth spaces in the blank, means for operating the die, and means to support the ends of the teeth formed in the blank, 5
10. 2. In a machine of the class described, in combination, a blank support, a die having teeth to form tooth spaces in the blank, means for operating the die, and means to support both the inner and the outer ends of the teeth formed in the blank.
15. 3. In a machine of the class described, in combination, a blank support, a die having teeth to form tooth spaces in the blank, means for operating the die and means formed integral with the support for supporting the ends of the teeth formed in the blank.
20. 4. In a machine of the class described, in combination, a blank support, a presser plate for holding the blank on said support, a die having teeth to form tooth spaces in the blank, said support and presser plate having projections for supporting the ends of the teeth formed in the blank and spaces 25 between said projections to receive the teeth of said die, and means for operating said die.
25. 5. In a machine of the class described, in combination, a blank support, a presser plate for holding the blank on said support, a die having teeth to form tooth spaces in the blank, said teeth being longer and extending beyond the ends of said tooth spaces, and said support and presser plate having projections for supporting the ends of the teeth 30 formed in the blank and spaces between said projections to receive the extended ends of said die teeth.
35. 6. In a machine of the class described, in combination, a support for an annular blank, a die, a locating member, means adapted to move the locating member be-
40. tween the die and blank to circumferentially position the latter relative to the former, and means for operating the die.
45. 7. In a machine of the class described, in combination, a blank support, a die having teeth to form tooth spaces in the blank, a locating member, means adapted to move the locating member between the die and the blank for positioning the latter relative to the former, and means for operating the die.
50. 8. In a machine of the class described, in combination, a blank support, a die having teeth to form tooth spaces in a toothed blank, a locating member having a tooth 55 adapted to enter a space formed in the blank and having a groove adapted to receive a tooth of said die for positioning the blank relative to the die, and means for operating the die.
55. 9. In a machine of the class described, in combination, a blank support, a die having teeth to form tooth spaces in a toothed blank, a pivoted locating member adapted to be swung into position between the die and 60 blank for positioning the latter relative to the former, and means for operating the die.
60. 10. In a machine of the class described, in combination, a blank support, a die having teeth to form tooth spaces in a toothed blank, a pivoted locating member adapted to be swung into position between the die and blank for positioning the latter relative to the former, a hand lever for operating said member, and means for operating the die.
65. 11. In a machine of the class described, in combination, a blank support, a die having teeth to form tooth spaces in a toothed blank, a pivoted locating member adapted to be swung into position between the die and 70 blank for positioning the latter relative to the former, a spring for holding said member normally in inoperative position, a hand lever for moving the member to operative position, and means for operating the die.
75. 80. 90. In testimony whereof I affix my signature.

FRANK F. BEALL.
